UNITED STATES PATENT OFFICE.

THOMAS S. ALLEN, OF MILWAUKEE, WISCONSIN, ASSIGNOR, BY MESNE ASSIGNMENTS,
TO ALLIS-CHALMERS MANUFACTURING COMPANY, A CORPORATION OF DELAWARE.

DYNAMO-ELECTRIC MACHINE.

1,197,092.

Specification of Letters Patent.

Patented Sept. 5, 1916.

Application filed April 15, 1910. Serial No. 555,620.

To all whom it may concern:

Be it known that I, THOMAS S. ALLEN, a citizen of the United States, residing at Milwaukee, in the county of Milwaukee and State of Wisconsin, have invented certain new and useful Improvements in Dynamo-Electric Machines, of which the following is a full, clear, and exact specification.

This invention relates to dynamo-electric machines, and particularly to revolving field members of high speed alternators, such as turbo-generators.

In certain types of dynamo-electric machines, and particularly in rotating field members of high speed machines, parts of the coils are under high stresses which tend to distort and displace the coils, and particularly the side portions thereof. These stresses are especially great in high speed rotating field members having a small number of pairs of poles, for in such machines the centrifugal force acting on certain parts of a coil may be divided into two components, one of which is at right angles to the face of the pole and tends to shift the coil laterally from the pole, and this component may be as large or even larger than the component which is parallel to the axis of the pole and is resisted by the pole tips.

To support the coils and to prevent their displacement at high speeds, coil bracing members have been employed, and these bracing members, each of which supports and braces the sides of the coils of two adjacent poles, are usually retained in position by fastening devices extending into the core of the rotating member. Such bracing members have not been satisfactory in all respects for the reason that they add to the weight of the machine, are frequently difficult to apply to the coils, and to adjust or tighten, and it is often the case that the means for fastening these bracing members in position materially weakens the core.

The object of the present invention is to provide coil supporting means which relieves the coils of the stresses tending to shift them outwardly or laterally from the pole, which is inexpensive, light in weight, and can be easily applied to the coils.

In carrying out my invention, I bind the coils firmly to the poles so as to relieve the side portions of the coils of the stresses, and preferably band wire is employed for this

purpose, each coil being wrapped at different points along its length by several turns of band wire. Preferably, spacing strips which may be formed of metal or insulating material, are placed lengthwise of the coil on the exterior thereof, and this band wire is wrapped tightly about these strips so that all portions of the coil are held against lateral displacement.

The invention may be further briefly summarized as consisting in certain combinations and arrangements of parts which will be described in the specification and set forth in the appended claims.

Reference is had to the accompanying sheet of drawings wherein—

Figure 1 is a side elevation of a dynamo-electric machine having a rotating field member, the coils of which are supported and braced in accordance with my invention; Fig. 2 is an enlarged side view of one of the field magnets; and, Fig. 3 is a transverse sectional view substantially along the line 3—3 of Fig. 2.

In the figures of the drawing, 10 represents the stationary element of the machine, which in this case is an armature, and 11 represents as a whole, the rotary element which in this case is a rotary field member. The rotary member includes a core 12, which is mounted upon a shaft 13, and field magnets 14, each comprising a core 15 and a coil 16, which may be formed of any suitable conductor and with any number of layers, but as shown in Fig. 3, is formed of several layers of square conductor 17.

The radial displacement of the coils due to that component of the centrifugal force acting on each part of a coil, parallel to the axis of the pole is resisted by pole tips or other polar projections 18 provided at the free end of the pole, but unless means is provided for relieving the sides of the coils of the stresses, they may be displaced or shifted laterally or outwardly away from the pole, and when a coil is built up of several layers of square conductor, as shown in Fig. 3, the turns at the inner end of the pole will tend to telescope with respect to the turns at the outer end. To securely hold all portions of the coils against lateral displacement, I bind each coil at a number of spaced points in its length by several turns of tightly wrapped band wire 19, and pref-

erably, I employ between the band wire and the coil longitudinally extending strips 20 which are arranged at the corners of the coil, and along the sides and ends thereof, 5 the strips being preferably spaced apart and forming passageways therebetween, as shown in the drawings, this construction leaving the portions of the coil surface uncovered by strips open to the atmosphere. 10 With this latter arrangement and with the binding material laid over the strips at spaced points, as shown in the drawings, the bearing of the binding material is distributed over the full axial length of the 15 coil with little or no danger of cutting into the same, and a considerable portion of the coil surface is open to the atmosphere, a condition which promotes efficient ventilation and cooling of the coil. These strips 20 may be formed of metal, providing the exterior of the coil is covered with a layer of coating of insulation, or they may be formed of insulating material, such as fiber. The turns of wire in each group, three of 25 which are shown in the drawings, may be soldered together opposite each of the strips 20, and the free ends of each group will be securely fastened so that the band wire will not become loose at any speed at which the 30 rotary field member may be operated.

It will be seen that the coil supporting and bracing means which I have provided is light in weight, can be very easily applied to a machine, is inexpensive, but will nevertheless hold all portions of the coils securely 35 in position.

Having thus described my invention, what I claim is:

1. In a dynamo-electric machine, a member having field magnets comprising radial poles and coils mounted thereon, means for preventing radial displacement of said coils, and means for preventing lateral displacement of said coils or portions thereof, said latter means comprising a plurality of 40 spaced strips laid along the exterior of each coil and in the general direction of the axis thereof, and spaced sections of banding material wrapped about said strips and extending in the general direction of the turns 45 of said coil. 50

2. In a dynamo-electric machine, a rotary element having field magnets comprising radial poles and coils mounted thereon, means for preventing radial displacement 55 of said coils, spaced strips extending longitudinally of the coils at the exterior thereof, certain of said strips being disposed at the corners of said coils and being made up of parts disposed at an angle to each other and engaging adjacent sides of the coils, and banding material wrapped about said strips and disposed in a plurality of spaced sections to prevent lateral displacement of 60 portions of said coils. 65

Milwaukee, Wis., April 11, 1910.

In testimony whereof I affix my signature, in the presence of two witnesses.

THOMAS S. ALLEN.
